UNITED STATES PATENT OFFICE.

GEORGE F. CARD, OF COVINGTON, KENTUCKY, ASSIGNOR TO HENRY K. LINDSEY, OF CINCINNATI, OHIO.

CAR-BRAKE.

SPECIFICATION forming part of Letters Patent No. 357,976, dated February 15, 1887.

Application filed December 26, 1885. Serial No. 186,737. (No model.)

To all whom it may concern:

Be it known that I, GEORGE F. CARD, of Covington, Kenton county, Kentucky, have invented a new and useful Improvement in Car-Brakes, of which the following is a specification.

This invention relates to the general class of devices whereby—at any instant of time—the momentum of a moving car or train may be utilized to retard or stop it.

10 In my present invention (like that described in my Patent No. 334,637, granted January 19, 1886, and to which reference may be made for features common to both forms) the brake mechanism is actuated through the instru-

15 mentality of an electro-magnetic circuit operating by mechanical appliances, which are partly automatic and partly under control of one or more officers of the train. In brake-operating devices of this kind anterior to my

20 said improvements the object has been accomplished by a counter-stress upon the system of weighted brake-levers by the direct action of the electro-magnetic armature, which has, consequently, required considerable length

25 or amplitude of stroke, with a corresponding expenditure of current force; but in my said improvements the pull upon the system of weighted levers is derived from the same member which drives the brake-windlass—namely,

30 one of the axles—through the medium of an electro-magnetic clutch. In my former invention the said clutch operated, when energized, to keep the brake mechanism proper out of action. In my present invention, on

35 the contrary, said clutch operates, when energized, to bring said mechanism into action. This mode of utilizing my electro-magnet possesses over that, of my former patent a still further marked economical gain consequent

40 on avoiding nearly all the wear and friction incident to contact of the revolving axle with the magnet-poles, such contact in my present form occurring only during the comparatively brief periods of brake action, instead of dur-

45 ing the greatly longer periods, during which no brake action takes place. In this mode of employing the electro-magnetic force the operating spring or weight of the brake mechanism is retractile and tends to hold the friction-drums out of contact, and instead of one

source of electricity, as in my aforesaid patent, two sources of electric current are required—one at each end of the train. These separate sources of current in my present invention consist of a dynamo on the locomotive and a 55 storage-battery on the rearmost car, the charge of said battery being maintained at the desired saturation by the shunting of almost the entire dynamo-current through it in the intervals between consecutive brake actions. For 60 this purpose I employ two electro-magnetic circuits—to wit: A circuit of low resistance, which I name the "charging-circuit," and a circuit of relatively much higher resistance, which I designate the "brake-circuit." The 65 said charging-circuit having served to maintain the battery-charge, as aforesaid, is grounded. The said brake-circuit is brought into activity by first cutting out the charging-circuit and then lowering the resistance in 70 said brake-circuit to the point required for applying the desired brake action with any force between that requisite for a slight slowing down to that necessary for abrupt stoppage of the train. The brake-circuit, besides 75 its higher resistance, differs from the charging-circuit in being completely "metallic," alike for the outgoing and for the returning currents.

My present improvement comprises a sys- 80 tem of regulatable resistances which operates as follows: First, in the normal condition of the brake-circuit, restricts its electro-magnetic activity to a point at which it is incapable of causing brake action; second, enables main- 85 tenance of a constant predetermined working-resistance under varying numbers of individual car-brakes included within it; third, en- ables the train-brakes to be operated from either source of electric current; fourth, ena- 90 bles either part of a separated train to be subjected to independent electro-magnetic brake action.

Associated with certain of these resistances are electro-magnetic sounders which, first, give 95 audible warning of train-separations and other disturbances; second, enable transmission of signals from either end of the train; third, prevent waste of battery energy.

The construction of my electro-magnetic 100

brake-couplings is such that by the mere act of bringing their parts together the charging-circuit and the brake-circuit are both made co-extensive with the train, and said construction is further such as, in event of separation of the train or of any brake-coupling, to automatically complete or close the brake-circuit for each portion of the train at the point of separation on the half of the coupling which remains attached to it, and to enable the full strength of the current on the separated part to flow from its source of electric energy (dynamo or battery) around the newly-formed terminus and back again to the said source.

In order to give instant notice of such new conditions, so as to warn the engineer to bring his now shortened brake-circuit to the desired normal resistance, and the conductor or other officer in charge of the separated rear portion to put the battery in communication with the brake system on his portion of the train, and, if occasion require, to set his brakes, each end of the train has a sounder which such change of conditions automatically brings into action in the manner hereinafter explained. The mechanism is so contrived as to automatically give instant warning of any variation of resistances, whether of increase, as by lengthening of the train, or of decrease, as by shortening or separation of it, or by cutting one or more cars out of the brake-circuit.

The present form of my invention is more especially designed and is here illustrated as adapted for use on freight-trains.

In the accompanying drawings, Figure 1 is a perspective view showing one of my electro-magnetic clutches in position upon the car-axle, the said figure representing the clutch in its open or inactive condition and its system of lever-and-chain connections with the friction-drums, and finally with the mechanism of the brake-shoe or rubber of any customary construction. Fig. 2 is a transverse, and Fig. 3 an axial, section of my electro-magnetic clutch in place upon the axle, the clutch in these two figures being shown energized, and consequently grasping the axle-collar. Fig. 4 is a diagrammatic representation of my double-circuit system, the said diagram being designed for a train consisting of an engine and two cars, the charging-circuit being shown closed. Fig. 5 represents diagrammatically the portion near and including the dynamo, the charging-circuit being shown cut out by a right-hand shift of the upper regulator-arm and the dynamo being shown cut out from the brake-circuit by the rupture of the combined cut-out and coupling between said circuit and the dynamo. Fig. 6 is a diagrammatic representation of the portion of my circuit system near to and including the storage-battery in the condition such portion assumes on a part of the train separated from what remains attached to the engine. In this condition of the parts the brake-circuit is seen to be automatically closed in the member of the ruptured coupling which remains attached to the thus-separated

portion of the train. This view supposes that the person in charge, having become (by ringing of the sounder or otherwise) cognizant of the disconnection of his part of the train from the part attached to the engine, has given the regulator-arm on his portion a right-hand shift sufficient to allow enough current to pass from the storage-battery into the coils of the electro-magnetic clutch to cause the segments of the latter to grasp the axle, as shown, preparatory to revolving with the latter a sufficient distance (see Fig. 2) to start the brake-windlass and set the brakes. Fig. 7 is a side elevation, and Fig. 8 is in part a front elevation and in part a section on line 8-8, of the two groups of resistance-regulators at the dynamo end, with associated high-resistance coil and sounder. The lower regulator-arm in Fig. 8 is represented set for a train having an engine and one attached car, and the upper regulator-arm in said figure is represented so set as to close the charging-circuit and to place all the resistance-coils in the brake-circuit, thus preventing brake action. Fig. 9 is a central vertical section of such resistance-groups. Fig. 10 is an elevation of the resistance-regulator and the sounder at the battery end, the regulator-arm being shown set for "down brakes" and the sounder-magnet being shown active. Fig. 11 is a top view of the sounder at the battery end, the bell having been removed and the magnet being shown inactive. Figs. 12 and 13 are perspective views in the closed and the open conditions, respectively, of the combined cut-out and coupling in the brake-circuit at the dynamo. Fig. 14 is a side elevation of my electric coupling between the locomotive and the foremost car, or between any two consecutive cars. Fig. 15 represents one member of my electric coupling in perspective. Fig. 16 shows my coupling in its detached condition, one member being represented by axial section and the other member by side elevation. Fig. 17 is an axial section of my coupling in the closed condition. Fig. 18 is a partial representation of my brake-setting group of resistances, the same showing a modification of my series of resistance-coils.

A may represent portions of either the locomotive and an attached car or of two consecutive cars.

B is part of a customary or any suitable brake-lever.

C may represent a part of one of the car-axes. D may represent part of a frame connected therewith.

E are cheeks, of which each is at one end formed into a sleeve which grasps the axle, and at the other end occupies a slot, f, in a bracket, F, upon the frame D. G is a U-formed lever, which has its fulcrum g in said cheeks E.

H is the brake-windlass, and I is a chain or cable that connects said windlass with one of the levers B of the brake apparatus proper, of any customary or approved construction.

The windlass H carries a spur-wheel, K, that

gears with a pinion, L, on shaft M, which is journaled in the arms of the lever G, and carries a friction wheel or drum, N, which, for setting the brakes, is by the motion of said lever brought into contact with a hub or collar, e, of the axle. The friction members or drums N e are held normally out of contact. This may be done by the gravity of the suspended mechanism of which the drum N is a member, 10 or by a special spring or counter-balance such as customarily employed in such devices.

A bracket, F', upon the frame D supports the fulcrum o of a bent lever, O, whose down-turned limb o' is coupled by pivot P to the lever G, and whose horizontally-extending limb o'' is connected by a chain or cable, Q, with an electro-magnetic clasp or clutch, R, whose construction is substantially as follows: Shrunk or formed upon the axle C is an iron hub or collar, e', loosely inclosing which are the two annular segmental jaws of my electro-magnetic clutch R, to which the said collar discharges the functions of an armature. Each jaw consists of two outer annular segmental cheeks, S, of any strong non-conductor—such as vulcanized fiber—connected at two of their adjacent extremities by a link or double joint, T, and at their other two extremities by a shackle, T', to which is fastened the lower end 30 of the chain Q. Secured between the cheeks S is an iron core, V, which, like said cheeks, is curved concentrically to the collar and has end expansions or pole-pieces, v, which, when the current is turned on, clasp the collar e', as shown in Figs. 2, 3, and 6. Surrounding each core is a helix, U, forming part of the brake-circuit hereinafter described. The winding of these helices is preferably in series, as shown. The cheeks S extend radially inward, 40 so as to embrace the shoulders of the collar e' and to hold the clutch against longitudinal displacement. The proportions of the parts are such that when current is traversing the helices U the jaws clasp the collar e' with force just sufficient to be carried around by the revolving axle to a point at which, through the media of the chains and levers above described, 45 they operate to cause effective impact of the friction-drums N and e, but not sufficient to 50 sunder the attachments by dragging the clutch around beyond that point, which being reached, the axle merely rotates within the clutch without causing further rotation of the latter. The double-jointed connection of the clutch-jaws 55 facilitates their embrace of the collar e' equally throughout.

The resistance, hereinafter described, and the helices of the clutch R are so proportioned as to produce a clutch-traction just sufficient for 60 the purpose without subjecting the parts to unnecessary wear and strain.

Actual tests show an insignificant stress (less than five pounds) to be amply sufficient to secure the necessary traction between the 65 clutch-jaws and the axle-collar, and this extremely slight tax upon the propelling power is, in the present form of my invention, re-

stricted to the comparatively brief periods of brake action.

Practical tests of the electro-magnetic clutch 70 show a capacity to stop a train of ten cars with less than one-fourth of an ampère of current.

The general arrangement of my circuit system is indicated in diagrams 4, 5, and 6, and 75 the mechanical details in other figures. 1, 2, and 3 respectively represent the charging-circuit, the brake-circuit, and the dynamo. The conductors 1 of the charging-circuit are represented by strong lines, and those, 2, of the 80 brake-circuit by faint lines, and their currents by strong and faint arrows respectively. Diagram 4 may represent the apparatus in condition to receive current.

To follow the path of the charging-circuit, 85 start from the positive pole of the dynamo 3 in direction of the strong arrows, through contact-springs 4 5 to the joined shells 6 of couplings, whose number depends on the number of cars composing the train. From the rear-most coupling the conductor passes to electro-magnet 7, of which its conductor forms the helices 8. Armature 9 of said magnet is normally held away from the magnet-core by customary retractile spring 10, whose tension is 90 made susceptible of regulation by its attachment to a common winding-post, 11, or by other customary means. This normal condition of the armature (shown in Figs. 6 and 11) brings it into juxtaposition with contact-spring 12. In this normal or quiescent condition of the parts communication exists through main conductor or short-cut 13 to contact-spring 12, thence through armature 9 and the conducting-wire to push-button 14, 105 through conductor 1^a and the metallic portions of the car to "ground." Similar communication exists from ground through the conductor 1^b and the engineer's push-button 15 to the negative pole of the dynamo 3. 110

Starting of the dynamo causes energization of electro magnet 7, so as to attract armature 9 and to rupture its contact with spring 12 and to bring its rear side in contact with spring 16. (See Figs. 4 and 10.) Direct communication with ground through short route 13 being thus cut out, the entire current of the helix 8 is compelled to traverse the shunt 1^c to the positive pole of storage-battery 17, through said battery to its negative pole, and 120 thence to the switch 18, which (when in the condition shown in Fig. 6 and by strong lines in Fig. 4) allows the current to proceed by conductor 1^d to the rear contact-spring 16, and thence through armature 9 to the ground, as 125 in the first instance.

The above description assumes that the springs 4 and 5 have been held in contact by pressure upon insulator-protuberance 19 on spring 4 of regulator-arm 20, to be hereinafter 130 described.

An important function of the electro-magnet 7 and its described associated spring contacts is that any tendency to reverse flow, and

consequent waste of battery-current, is checked by rupture of the battery-circuit at the point of contact of armature 9 with the contact-spring 12. The importance of such automatic interruption is apparent when it is perceived that such reflex current action might ensue either from a weakening or a cessation of the dynamo-current, or even by the electro-motive force of the dynamo dropping below the accumulated force of the battery. Audible notification of such condition of the parts is given by any suitable sounder—such, for example, as may consist of a bell, 21, struck by a hammer, 22, on end of armature 9, at each retractile stroke thereof. The same sounder is available as a means by which the person in charge at the rear end of the train can be signaled by the engineer, as the bell 21 can at any instant be rung by a momentary depression of push-button, 15.

23 is a resistance-coil for the purpose of preventing any change of current intensity in the battery-circuit which may arise from cutting out the battery.

25 To cut out the battery the switch 18 is shifted to break the communication with the battery and make communication with the said coil 23. (See dotted lines in Fig. 4.)

In the above-described condition of the parts 30 the apparatus possesses, in multiple, two circuits complete, to wit: the charging-circuit of low resistance and the brake-circuit of very high resistance, whose respective current strengths are inversely as their resistances.

35 Before entering on a general description of my brake-operating circuit explanation will be made of several groups of included resistances. Of these groups the first to be described is resistance-group 34, which is an instrumentality whereby the engineer is enabled to keep the resistance of the entire brake-circuit constant, notwithstanding changes in the number of individual car-brakes included in the circuit. This group is preferably located 40 in the return branch of the brake-circuit near the dynamo, and consists of a vibrating arm, 35, in said circuit, concentric with whose axis of vibration is a series of contact-plates, 36, connected by coils 37, the resistance of each 45 of which should equal that of an individual car-brake, and whose number should correspond to that of the greatest number of such brakes likely to be coupled up in a single train. Short-cut switches 38, or other proper expedients, enable the person in charge of the train 50 to include or exclude, at discretion, any one or more of the individual car-brakes. In using the device 34 the engineer cuts out as many coils as there are brakes to be operated, thus 55 Fig. 4 shows the device adapted for two, and Figs. 5 and 8 for one brake. For simplicity of illustration only five coils are here shown.

60 Of similar construction to group 34 is the resistance-group 39, which is an instrumentality whereby the engineer is enabled to first cut out the charging-circuit and to next bring the brakes into action with any desired force—that

is to say, from that which barely suffices to slow down the train to a force capable of stopping the train either gradually or with any desired abruptness. Said group has a regulating-arm, 20, similar both in arrangement and function to arm 35 of group 34, but possessing, when in the depressed position shown in Figs. 4 and 8, the further function of holding the 75 springs 4 and 5 in contact, which it does by its impact with the non-conducting protuberance 19 on spring 4. Associated with arm 20 is a series of contact-plates, 42, similar in arrangement and function to the contact-plates 36 of group 34. The first two contact-plates of group 39 are connected by the very-high-resistance coil 43 of an electro-magnet, 7*, whose armature 9* is normally held away from said electro-magnet by retractile spring 10*, so as to 80 come against adjustable contact-point 30, and to thereby establish communication from the first of contact-plates 42, through said contact-point 30, to the armature 9, and thence through the coil 43 to the second of said contact-plates. 85 The resistance of the coil 43 is made sufficient to completely prevent brake action even after the charging-circuit has been cut out by the first slight elevation of regulator-arm 20, or by the rupture of the charging-circuit at any other 90 point. The retracting-spring 10* is attached to winding-post 11*, and its tension is so adjusted as, with the normal resistance in the brake-circuit, to hold the armature 9* against contact-point 30, except when the brake-circuit current attains the certain predetermined 95 strength, which ensues upon interruption of the charging-circuit, when the armature is pulled away from contact-point 30 by the electro-magnet 7*, so as to rupture the brake-circuit, and is then alternately pulled in one direction by the spring 30 and in the other direction by the electro-magnet, so as to alternately close and open the brake-circuit until the normal current therein is restored. The 100 armature 9* carries a hammer, 22*, which, when said armature vibrates, strikes a bell, 21*, so that the device constitutes a repeating-sounder, which informs the engineer of any interruption of the charging-circuit, which 105 may be caused by the separation of the train or by depression of push-button 14 by the person in charge at the rear end of the train, who 110 is thereby enabled to signal the engineer.

The resistance in the brake-circuit may be 115 so proportioned that the exclusion from the brake-circuit of one or more individual car-brakes while the charging-circuit remains closed will cause the sounder 21* to ring until, by shifting arm 35, the normal brake-circuit 120 resistance is again established. Such decrease in resistance of the brake-circuit with the charging-circuit still closed may be caused by shifting one or more of the switches 38, or by 125 shortening the train by the persons in charge, in which latter case the storage-battery is removed to the rear car of the newly-made-up 130 train and the charging and brake circuits completed, as before.

The second and third and all succeeding consecutive contact-plates of group 39 are connected by coils 49, preferably of much higher resistance than the coils 37 of group 34. These 5 coils may be all of uniform resistance; but by preference the coil first encountered in setting the brakes will be of greater resistance, the next consecutive coil of somewhat less resistance than the first, and so on, with diminishing resistances, down to the other end of the group. This may be secured either by using wires of gradually greater thicknesses for the successive coils, (which may be supposed to be the case in Fig. 8,) or coils of gradually- 15 lessening lengths of wire, which latter form is intended to be represented in Fig. 18. The contact-plates of each group are preferably of the represented segmental form, arranged in an annular segment whose outer periphery is 20 concentric with the axis of vibration of the regulating-arm, and each arm has a contact-piece, 50, which is caused to press against said periphery by means of a spiral spring, 51. Each arm has also a convenient handle, 52. 25 Of the two groups of regulating-resistance, 34 and 39, group 34 is set once for all for any particular train immediately after such train has been made up, and is then left wholly undisturbed until some change in the train takes 30 place, either by addition or removal of individual car-brakes. Group 39, on the contrary, remains undisturbed and in its normal condition (shown in Figs. 4 and 8) until it becomes necessary to apply the brakes, for which 35 purpose the arm 20 is moved to the right to a less or greater extent, according to the urgency of the situation. Fig. 18 shows the arm set for a strong brake action, only one, and that the feeblest, coil remaining in circuit.

40 The operation of the resistance-group 34 may be illustrated by supposing it to comprise ten or more resistance-coils and to be employed on a train with ten individual car-brakes in the brake-circuit, with a total resistance of 6.5 ohms. Let the number be reduced to nine, either by removal of a car from the train or by cutting its brake-system out of circuit, the resistance will be reduced to 5.85 ohms. Now shift the arm 35 so as to bring an 45 additional resistance-coil into the circuit, and the normal resistance, 6.5 ohms, is at once restored, and this may be repeated up to the limit of the resistance-regulator.

In addition to the above-described groups of 55 resistance-regulators at or near the front end of the brake-circuit, I provide in the portion of said circuit most remote from the dynamo a third resistance-group, 55, whose construction and functions are similar to those of group 39. The purpose of said group 55 is to enable 60 operation of the brakes by means of the storage-battery, either upon a part of the train which is purposely or accidentally severed from that in front of it or on an unbroken 65 train in event of the giving out of the dynamo or cessation of its functions from any cause.

Like the groups previously spoken of, group 55 has a vibrating regulating-arm, 56, and a semi-annular series of contact-plates, 57, and resistance-coils 58, of identical structure and 70 functions with like members in group 39. Said group 55 and its herein-described accessories are preferably mounted on a box, 26, which may serve as a place of attachment for electro-magnet 7, push-button 14, and various 75 binding-posts 53. Further explanation of said group 55 is deferred until the general description of the brake-circuit in its various conditions.

Both the outgoing and returning branches 80 of the brake-circuit 2 connect with a combined duplex cut-out and coupler, X, which may be constructed as follows: 59 is a plate or slab, of any tough non-conductor, such as ebonite or vulcanized fiber. Fastened to slab 59 85 are two contact-plates, 60 61, to which are respectively fastened the ruptured ends of the outgoing branch 2^a of the brake-circuit; also fastened to the same slab are two other contact-plates, 62 63, to which are respectively 90 fastened the ruptured ends of the returning branch 2^a of the brake-circuit. Secured to slab 59 by spring-clip 64 is a sliding bridge 65, to whose ebonite bar 66 are fastened three spring-contacts, 67 68 69. In the condition of 95 the device shown in Figs. 4 and 12 the springs 67 and 68, by pressing, respectively, on the plates 60 and 61 of the outgoing and 62 and 63 of the returning branch, complete the circuit through the dynamo. In the condition of the 100 device shown in Figs. 5 and 13 the dynamo is cut out and the spring 69, by pressing on plates 61 and 63, connects the outgoing and returning wires independently of the dynamo.

In order that the brake-circuit may be in condition for normal action, the following precautions are necessary: The slide or bridge 65 of the combined cut-out and coupler X being so placed as to include the dynamo, (see Figs. 4 and 12,) the couplings of the several individual car-brakes are joined. (See Figs. 4, 14, and 17.) The arm 56 is depressed (see Fig. 4) so as, by pressing on insulator 31 on spring 28, to bring said spring into contact with spring 27 and to separate it from contact-point 29, thereby completing the brake-circuit at the rear end with exclusion of the storage-battery, and the arm 35 is adjusted (see Fig. 4) to secure the predetermined normal resistance. To follow the thus-completed brake-circuit, we start from the 110 positive pole of the dynamo through the outgoing-channel 60 67 61 of the combined cut-out and coupler X to regulator-arm 20, thence through the contact-plates and resistance-coils of group 39 through the outgoing interior connections of the successive couplings Y, thence 115 through contact-springs 27 28 to the return-wire 2^a, which leads forward through the successive electro-magnetic clamps R and the return-channels of the interposed couplings Y 120 to regulator-arm 35, thence through the included contact-plates and resistance-coils of 125 130

group 34, and through return-channel 62 68 63 of combined cut-out and coupler X to the negative pole of the dynamo.

To set the brakes the engineer first lifts the 5 arm 20, so as to release the contact-springs 4 5, and to thereby rupture the charging-circuit and restrict the entire dynamo force to the 10 brake-circuit, and then moves said arm as much to the right as will suffice to throw out 15 of the brake-circuit enough resistance of group 39 to lower the resistance of said brake-circuit to a point at which the dynamo is enabled to produce a current therein sufficient for the desired brake action.

15 Should the dynamo give out or be stopped for any purpose, the engineer, having first signaled the fact to the conductor, cuts out the dynamo from the brake-circuit by a left-hand shift of slide 65. (See Fig. 5.) The conductor 20 then, by shifting arm 56 to the extreme right, cuts out from the brake-circuit all the resistances of group 55 and permits the resilience of spring 28 to bring it out of juxtaposition with spring 27 and into juxtaposition with 25 contact-point 29. These manipulations place the battery in the brake-circuit and enable the engineer to control the brakes by the current from the same. Should he now wish to set the train-brakes, he shifts regulator-arm 20 30 to the right sufficiently to cut out of the brake-circuit enough resistance to enable the charge accumulated in the storage-battery to escape sufficiently to cause brake action, the path of the current being, as per dotted arrows, from 35 the positive pole of said battery through contact-point 29 and spring 28, and successive conductors 2ⁿ, electro-magnetic clutches R, and lower interior channel of couplings Y to arm 35, thence through included resistance-coils of 40 group 34 and around the now bridged coupling X to arm 20, thence through the included resistance of group 39, along conductor 2ⁿ and upper interior channel of couplings Y to arm 56, and thence by wire into storage-battery at 45 its negative pole.

Should the train part, say at point *, the two branches of the brake-circuit become (in consequence of the peculiar construction of the couplings Y, to be presently explained,) 50 connected together on each half of the severed coupling, so as to form on the rear portion of the train a closed circuit, including the storage-battery, and on the front portion of the train another closed circuit, which includes 55 the dynamo. This being the case, the engineer may, if he so desire, set his brakes from the dynamo, as before, by decreasing the number of resistances of group 39 included in the brake-circuit, the current now, however, proceeding rearward only to the forward half of the severed coupling, in which it passes on to the return-wire, which leads it forward, as before. The person in charge at the rear end of the train is also enabled to set the brakes on 65 the severed portion by lifting arm 56, to allow spring 28 to break contact with spring 27 and to close with contact-point 29, thus throw-

ing the storage-battery and the resistances of group 55 in circuit, and by moving said arm 56 sufficiently to the right to exclude enough 70 of said resistances from the brake-circuit to enable the storage-battery to produce the requisite current therein for the desired brake action, said current now passing forward through one wire of the brake-circuit only to the rear half 75 of the severed coupling, and then through said coupling and back through the other wire. When the number of cars in the train is changed by the persons in charge of the train, the storage-battery is removed to the rear car 80 of the reconstructed train.

The two groups 34 39, although of like forms and cognate functions in a general sense, are wholly distinct from and independent of one another and for the different uses mentioned, 85 and are preferably located in electrically remote parts of the brake-circuit. They may also be remote in space, as indicated in Figs. 4 and 5, but for compactness in construction and convenience of manipulation they are preferably 90 located about a common geometrical axis on a single box, 48, which may be utilized for a place of attachment of various adjuncts—such as binding-posts 53 and the contact-springs 32 33 of the arms 20 and 35, respectively, 95 likewise of the high-resistance electro-magnet and sounder 7*. Such box may also be utilized as a place of attachment for the push-button 15 in the charging-circuit, in convenient position for the engineer to ring the 100 sounder at the remote end of the train.

The two halves of the coupling devised by me for use with the above-described system of electro-magnetic circuits being of identical construction, description of one half will serve 105 for both.

1 may represent a portion of the charging-wire. 2ⁿ may represent a portion of the brake-circuit wire which conveys the outgoing current, and 2ⁿ may represent a portion of the 110 brake-circuit wire which conveys the returning current. Each of these three wires is wrapped with any customary insulating material. The bared end of wire 1 is soldered to or by other means brought into intimate metallic contact with a shell, 6, preferably of the represented notched form 70 at its mouth, and having attached to its indented side a lip, 71, whose longitudinal slits 72 enable it to receive the salient portion 73 of the opposing 115 half of the coupling and to embrace it so tightly as to insure electrical connection and to prevent accidental separation from any force less than that of uncoupling of the two vehicles. It will be seen that complete communication is thus provided through any number of cars for the single outgoing conductor of the charging circuit. The bared ends of the two wires 2ⁿ and 2ⁿ of the brake-circuit are brought into intimate metallic contact, by 120 soldering or otherwise, with springs 74 75, which are separated from one another by insulating-plate 76, of vulcanized fiber or other suitable non-conductor, which is fastened to 125

spring 74 by a screw, 77, that also serves as a contact-point for the spring 75 of the opposing half of the coupling in the joined condition thereof. These springs are by preference given 5 the forms, respectively, here shown—that is to say, spring 74 is bent somewhat abruptly outward, then more gradually and for a greater part of its length inward, and terminates in an out-curved lip, 78, to facilitate the 10 introduction of corresponding members of the opposing half.

Spring 75 is bent at first abruptly outward and then more gradually inward, then abruptly inward, and terminates in a tongue, 79, 15 which, extending straight forward, presses against lip 78 in the parted condition of the coupling, and projects considerably beyond said lip, so as to facilitate the proper impact of the two halves, as shown in Fig. 16, and to 20 secure contact with the point 77 of the opposing half in the joined condition of the coupling, as seen in Fig. 17. Proper entrance and efficient contact of these parts may be, and is preferably, insured by the addition to each 25 spring 74 75 of one or more auxiliary springs, to wit: to spring 74, the springs 80 81, and to spring 75 of an auxiliary spring, 83. Of said springs 80 81 the outermost spring, 81, has an oblique lip, 82, which aids in guiding the long 30 tongue 79 of the opposing half to its place, and when driven home aids in holding it to close contact, and also forms an additional contact and channel for the current. The auxiliary spring 83, at back of spring 75, in 35 like manner assists to secure contact and adds conducting facilities. Sheaths 84 85 on auxiliary springs 80 83 assist in holding the springs 74 75 against lateral displacement.

The above-described construction of parts 40 causes the springs 74 and 75 to come into close contact with each other, and to thus make electrical connection, and to close the circuit at that point on withdrawal of the opposing half, as clearly shown in Figs. 6, 15, and 16.

Engagement of the two halves of the coupling is facilitated by giving a chamfered form, 45 as at 73^a 76^a, to the advancing edges of the shells and insulating-plates, respectively.

The exposed portions of the groups of conductors 1 2^a 2^b are protected by india-rubber or other suitable sleeves or coverings, 86, secured by metallic bands 86^a, or other suitable means.

The portions of the conductors under the 55 car-body may consist of iron bars 87 88 89, having proper insulated attachment to the body.

The expression "rear car" as employed in this specification is intended to designate the 60 car which carries the storage-battery of my described system, and which in freight-trains will generally be that known as the "caboose;" but the expression does not necessarily imply that there are no cars behind the so-called 65 "rear car," because occasionally the contrary will be the case. Such cars are not necessarily included in the brake-circuit, or if included,

may be coupled up in direct series with the cars in front of the caboose, so that in any case the brake mechanism of the caboose will 70 be in the part of the circuit which is, electrically speaking, most remote from the dynamo.

The specification describes two sources of electric current upon the locomotive and the rear car, respectively, of which one source is 75 a storer of electricity derived from the other and primary source, preferably a dynamo-generator, through a conductor distinct from and of lower resistance than the brake-circuit proper, through which latter the current from 80 either source may be directed at will for brake action.

An important modification of the above arrangement may have each magazine of electricity to consist of a storage-battery. Supplies of such batteries being kept charged in 85 convenient depots, a sufficient number may be placed on the train for purposes of substitution of fresh for exhausted batteries. Such an arrangement may comprise a brake-circuit 90 supplied with electro-magnets, electric couplings, and regulatable resistances or rheostats substantially identical with those hereinabove described.

In this form of my improvement the source 95 of electricity near the head of the train is not necessarily upon the locomotive, but may be located on the car immediately attached thereto.

Modifications or developments of my electro-magnetic brake system, such as above referred to, are the subjects of applications for Patents Nos. 207,247 and 224,591, to which reference may be made for descriptions of details appropriate to the present device. 100

I claim as new and of my invention—

1. A brake system for railway-trains, which has an electro-magnetic circuit which comprises, in the described combination, a brake-operating electro-magnet on each car, two 110 sources of electricity (having each one or more series of regulatable resistances) located respectively on the terminal vehicles in the circuits, and a pair of two-way self-closing electric couplings between each two consecutive 115 vehicles, substantially as and for the purposes set forth.

2. An electro-magnetic brake system in which, combined with one of the car-axles, is an embracing electro-magnetic clasp or clutch 120 in an electric circuit which comprises two or more rheostats or series of resistance-coils made capable of being partially or wholly cut in or out of circuit by shiftable contacts under control of the operator, combined, in the manner substantially as described, with a brake-setting mechanism which is brought into activity by cutting out one or more of said resistances.

3. In an electro-magnetic brake system, the 130 combination of the following elements, to wit: a car-axle, an embracing electro-magnetic clutch normally out of contact with said axle, excludable electric resistances in the clutch-

circuit, a brake-setting mechanism coupled to said clutch and whose friction-drum is held normally out of contact with that on the axle, and means of cutting out one or more of said resistances to produce and regulate brake action, in the manner explained.

4. In an electro-magnetic brake system, the combination of the following elements, to wit: a closed circuit including a source of electricity; one or more couplings having separately-insulated conductors for the outgoing and return currents also in said circuit; two independent groups of resistances also in said circuit, having shiftable contacts under the control of the operator for partially or wholly cutting into or out of the circuit the said resistances; an electro-magnetic clutch; an axle acting as armature to the magnet of said clutch, and brake-setting mechanism having a brake-windlass drum held normally aloof from the driving-axle and connected to said clutch mechanism, so that the said drum and axle are brought into contact by vitalization of the clutch-magnet, substantially as set forth.

25 5. In an electro-magnetic brake system for railway-trains, in combination with an electro-magnetic clutch on a car, a brake-circuit including the electro-magnet of said clutch and the following additional elements, to wit: a source of electricity, a closed conductor to and from the rearmost car, and a group of electrical resistances having the described regulator-arm, whereby the total resistance of the brake-circuit may be kept constant, whatever be the number of individual car-brakes included in the circuit, substantially as set forth.

6. In an electro-magnetic brake system for railway-trains, the combination of the following elements, to wit: a car-wheel axle, a normally-inactive electro-magnetic clutch which embraces said axle, brake mechanism held normally aloof from said axle and to which said clutch is mechanically connected, said brake mechanism consisting of brake-windlass II, geared drum N, and swinging bearing G, and said clutch being in circuit with a source of electricity containing one or more includable resistance-shunts, as and for the purposes set forth.

50 7. In an electro-magnetic brake system for railway-trains, in combination with an electro-magnetic clutch on a car, a brake-circuit including the electro-magnet of said clutch, and the following additional elements, to wit: a source of electricity, a closed conductor to and from the rearmost car, and a group of gradually-decreasing resistances from the normal to the fully active positions of the regulator-arm for production or modification of brake action, substantially as set forth.

8. In an electro-magnetic brake system, the combination of the following elements, to wit: a source of electricity and a closed circuit, couplings in said circuit that contain separately-insulated conductors for the outgoing and the returning currents, said circuit also including two independent groups of resist-

ance-coils having shiftable contacts to enable them to be cut in or out of circuit, and an electro-magnetic clutch having said axle for its armature, so as when energized to share the latter's rotation and to pull and hold the brake-windlass down into effective axle-contact, in the manner explained.

9. In an electro-magnetic brake system, in combination with an electro-magnetic clutch on a car, a brake-circuit including the electro-magnet of said clutch, and the following additional elements, to wit: a source of electricity, a closed conductor to and from the rearmost car, and the two associated groups of regulatable resistances, 34 39, substantially as and for the purposes explained.

10. In an electro-magnetic brake system, in combination with an electro-magnetic clutch on a car, a brake-circuit including the electro-magnet of said clutch, and the following additional elements, to wit: a source of electricity, a closed conductor to and from the rearmost car, and the two concentrically-associated semi-annular groups of resistances 34 39, whose respective regulator-arms 35 20 are pivoted about a common center or axis of motion, as set forth and described.

11. An electro-magnetic brake system for railway-trains, which comprises a dynamo upon the locomotive and a storage-battery charged therefrom upon a distant part of the train in two electric circuits, to wit: a grounded charging-circuit and a brake-circuit of relatively high resistance that includes a normally-inactive electro-magnetic clutch upon an axle of each car in the train, the whole being combined and operating as described.

12. An electro-magnetic brake system for railway-trains, which comprises, in the described combination, a grounded dynamo upon the locomotive, a charging-circuit therefrom to a grounded storage-battery at the remote extremity of the train, and a relatively high-resistance brake-circuit which includes on each car an electro-magnetic clutch which, when energized, clasps and shares the rotation of an axle thereof and has mechanical connection with a brake-setting mechanism held normally aloof from the axle, a three-way coupling between each two consecutive cars, and two groups of resistance-coils, of which one serves to maintain a constant normal resistance of brake-circuit and the other to control brake action by means of a regulator-arm whose movement serves to sever the charging-circuit by the means and in the manner designated.

13. An electro-magnetic brake system which comprises, in the described combination, a charging-circuit from a grounded dynamo upon the locomotive to a distant grounded storage-battery upon the train, and a brake-circuit containing an electro-magnetic clutch on each car, having the described combination with an axle thereof, so as when vitalized, to clasp and share the motion of the same, and having the described connection with the

brake-setting mechanism and with three-way couplings by which said brake-circuit is completed from the dynamo rearward, and again forward from car to car back again to the dynamo, as set forth.

14. In an electro-magnetic brake system for railway-trains, in combination with a source of electricity, a storage-battery, and an electro-magnetic clutch on a car, charging and braking circuits, the latter including the magnet of said clutch, and two associated rheostats or groups of resistances, 34 and 39, having independent contact-arms, of which group 34 enables the operator to keep the resistance of the entire brake-circuit constant under varying numbers of individual car-brakes included in the circuit, and group 39 enables him to cut out the charging-circuit and to produce the desired brake action, substantially as and for the purpose set forth.

15. In combination with a brake-windlass and a friction-drum thereupon, held normally aloof from the car-axle, an electro-magnetic brake system for railway-trains, which comprises a dynamo upon the locomotive, and a storage-battery charged therefrom in two electric circuits, to wit: a grounded charging-circuit and a brake-circuit of relatively-high resistance, which circuit includes a normally-inactive electro-magnetic clutch upon an axle of each car in the train, said clutch having mechanical connection to the drum-windlass bearing, as set forth.

16. In an electro-magnetic brake system for railway-trains, the combination of a grounded dynamo at one end of the train, a grounded storage-battery distant therefrom, a charging-circuit from one to the other, a brake magnet on a car and its circuit, and an electro-magnetic check and rheotrope in said charging-circuit, consisting of electro-magnet 7, retractile armature 9, front and rear contacts, 12 16, switch 18, and the alternatively-operating main and shunted branches of said charging-circuit, the whole arranged and adapted to operate substantially as set forth, whereby any tendency to reverse flow of battery-current is automatically prevented.

17. In an electric apparatus for operating railway-brakes, the combination, with a dynamo upon the locomotive, the normal ground-connection of whose positive wire is through electro-magnet helix 8, storage-battery 17, rear contact, 16, and armature 9, of the contact-piece or cut-out 12, whereby refulent current from an overcharged battery is automatically prevented, as set forth.

18. In an electric apparatus for operating railway-brakes, the combination, with a dynamo upon the locomotive, the normal ground-connection of whose positive wire is through electro-magnet helix 8, conductor 1°, storage-battery 17, conductor 1°, rear contact, 16, and the retractile armature 9, of cut-out 12, arranged to contact with said armature when released by said magnet and having proper ground-connection, and sounder 21, arranged

in proximity to said armature, as and for the purposes set forth.

19. In an electric apparatus for working railway-car brakes, a secondary source of electricity charged from a distant electrical generator on the same train, and the normal ground-connection of whose positive wire is through an electro-magnet having a cut-out and sounder, 75 for the double purpose of preventing reflux of the battery-current and of giving audible intimation of surcharge of said secondary source, substantially as set forth.

20. The brake-circuit consisting of dynamo 80 3, outgoing and returning conductors 2° 2ⁿ, groups of controllable resistances 34 39, combined charging-circuit, cut-out, and brake-regulator arm 20, and contact-springs 4 5, the contact-springs 27 28, and the electro-magnetic clutch-helices U, as set forth.

21. In an electric apparatus for working car-brakes, in combination with a means for simultaneously cutting out the dynamo and closing the brake-circuit at the point of such contact, and with a storage-battery and a shunt-circuit, the shiftable contact 29, arm 56, and the series of graduated resistances 58, to enable application of the accumulated potential force of the battery to the setting of the 95 brakes from the rear of the train and independently of the dynamo, in the manner explained.

22. In an electrical apparatus for working car-brakes, the combination, in the brake-circuit, of the following elements, to wit: two-way electric couplings Y from car to car, electro-magnetic clutches R, controlling the brake-windlass, and the two groups 34 and 55 of regulatable resistances at remote ends of the train, 100 105 and for the several purposes explained.

23. In an electrical apparatus for working car-brakes, the combination, in the brake-circuit, of the following elements, to wit: two-way electric couplings Y from car to car, electro-magnetic clutches R, controlling the brake-windlass, and the three groups 34, 39, and 55 of regulatable resistances, as and for the purposes set forth.

24. In an electro-magnetic brake system for 115 railway-trains, in combination with an electro-magnetic clutch on a car and a circuit including the electro-magnet of said clutch, the following elements, to wit: a source of electricity, fixed contacts 42, a movable contact, 120 20, adapted to be placed on either of said fixed contacts, high-resistance electro-magnet 43, and its associated sounder 7*, as and for the purposes designated.

25. In an electro-magnetic brake system, in 125 combination with a dynamo, a distant storage-battery, and a connecting brake-circuit, a brake-magnet on a car and resistances in said circuit, the latter having means of regulation, substantially as set forth, and a combined two-way coupler and cut-out arranged between the said dynamo and resistances in such manner that whether the brake-magnet be energized by current from the dynamo or from the bat-

teries the said resistances will be in circuit with said magnet, substantially as set forth.

26. The combination of the dynamo 3, the storage-battery 17, the conductors 1 1^a 1^b, the 5 electro-magnet 7, the retractile armature 9, the contact-springs 12 and 16, the resistance-coil 23, and the switch 18, as and for the purpose designated.

27. In combination with the divided conductors, to wit: the divided conductor 1 of the charging-circuit and the divided outgoing and returning conductors 2^a 2^b of the brake-circuit, the three-way coupling of which each half comprises a conducting and grasping 15 shell, 6, adapted to engage tightly with its fellow, and insulated contact-springs 74 75, constructed and operating substantially as and for the purpose set forth.

28. In combination with the divided conductor 1 for the outgoing current of the charging-circuit and with the divided conductors 2^a 2^b for the outgoing and the return currents of the brake-circuit, the three-way coupling of which each half comprises a conducting and

fastening shell, 6, having notched and chamfered advancing edges and the elastic lip 71, and the insulated contact-springs 74 75, as set forth.

29. In combination with the divided conductor 1 for the outgoing current of the 30 grounded or charging circuit and with the divided conductors 2^a 2^b for the outgoing and the returning currents of the brake-circuit, the three-way coupling of which each half comprises a notched and chamfered conduct- 35 ing and fastening shell, 6, and insulating-plate 76, a fastening and contact screw, 77, the main contact-springs 74 75, and the auxiliary spring 8, having the oblique lip 82.

30. In combination with the main contact- 40 springs 74 75, the auxiliary springs 80 83, having the guide sheaths or stays 84 85.

In testimony of which invention I hereunto set my hand.
